UPGRADING CATALYTIC C₅ HYDROCARBONS

Donald L. Baeder, Fanwood, N.J., assignor to Esso Research and Engineering Company, a corporation of Delaware

Filed Dec. 20, 1956, Ser. No. 629,508

6 Claims. (Cl. 260—683.9)

This invention relates to an improved process for upgrading a catalytic C₅ hydrocarbon fraction. More particularly it relates to a process wherein fractions of this nature are upgraded by a combination of treatment with a molecular sieve followed by hydrogenation of the effluent.

One of the most important requirements of a high quality gasoline at the present time relates to the anti-knock rating of the gasoline. The importance of gasolines of high anti-knock rating has been made more and more critical by the trend toward engines of higher compression ratio. At the present time the compression ratio of current automobile engines has been increased to values above 6.5, ranging upwardly to as high as 12. Engines having such high compression ratios require use of high anti-knock gasolines. The more extended use of automatic transmissions has also aggravated the problem of satisfying the octane requirements of current automotive engines. In the past, octane ratings of gasolines have primarily been determined by ASTM test, designated D908—47T. While this is an important and valuable anti-knock rating test, it has become appreciated that the Research octane rating of a gasoline as determined by this method correlates poorly with actual road performance of a gasoline. This is true in part since the Research octane number is determined in a test procedure at which the engine is operated at conditions of constant speed and constant load. As opposed to this, the actual knocking tendency of a fuel in road performance is greatest during maximum load. It is therefore appreciated at this time that the Research octane number rating of a gasoline is not a complete indication of the value of a gasoline in satisfying an engine under road conditions.

As a result, other methods of determining octane ratings are commonly employed. One such method is the so-called motor method test, designated by ASTM test Method D357—47. It has been found that the motor method octane determination correlates with the road performance of a gasoline somewhat better than the Research octane rating.

In view of these basic factors, production of present day high quality gasolines must be carried out with reference to both the Research and Motor method octane rating. The over-all octane rating of the fuel is some function of both of these octane rating methods and can be approximated by averaging the Research and Motor method ratings.

It has been appreciated that catalytic C₅ hydrocarbon fractions have utility as blending agents for increased octane ratings of finished gasolines. Certain of the C₅ components, after hydrogenation, are more useful for this purpose than others.

This invention provides a method for upgrading catalytic C₅ hydrocarbon fractions to improve their Research and particularly Motor octane numbers. The method comprises briefly, passing the catalytic C₅ hydrocarbon fraction through a molecular sieve adsorption zone so as to remove therefrom substantially all the normal hydrocarbons. The normal hydrocarbon-free effluent from the

2

adsorption zone is then hydrogenated for complete saturation in the presence of a hydrogenation catalyst.

The catalytic C₅ hydrocarbon fraction which constitutes the feed for the process of this invention is that obtained from conventional catalytic cracking of petroleum gas oils. This fraction typically boils in the range of 75° to 115° F. and contains some C₄'s. A typical composition is as follows:

Analysis of typical (Baytown) catalytic C ₅ stream		Vol. percent
Butanes	-----	0.6
Butenes	-----	2.6
Isopentane	-----	42.2
15 n-Pentane	-----	5.0
2-methylbutene-1	-----	11.6
Pentene-1	-----	7.6
Cis-pentene-2	-----	5.8
trans-pentene-2	-----	9.2
20 2-methylbutene-2	-----	15.0
Pentadienes	-----	0.4

The molecular sieves utilized are known. The scientific and patent literature contains numerous references to the sieving action of natural and synthetic zeolites. Among the natural zeolites having this sieving property may be mentioned chabazites. A synthetic zeolite with molecular sieve properties is described in U.S. Patent 2,424,191. Zeolites vary somewhat in composition but generally contain the elements silicon, aluminum, and oxygen as well as an alkali metal and/or an alkaline earth metal element, e.g., sodium and/or calcium. The naturally occurring zeolite, analcrite, for instance, has the empirical formula NaAlSi₂O₆·H₂O. Barrer, U.S. Patent 2,306,610, teaches that all or part of the sodium is replaceable by calcium to yield, on dehydration, a molecular sieve having the formula (Ca,Na₂) Al₂Si₄O₁₂. Black, U.S. Patent 2,522,426, describes a synthetic molecular sieve zeolite having the formula 4CaO·Al₂O₃·4SiO₂. A large number of other naturally occurring zeolites having molecular sieve activity, i.e., the ability to adsorb straight chain hydrocarbons and exclude the branch chain isomers due to differences in molecular size, are known. The pores in different zeolites may vary in diameter from less than 3 or 4 to 15 or more Angstrom units, but for any one zeolite the pores are substantially of uniform size. It is preferred to use zeolites having pore openings of about 5 Angstroms, e.g., calcium aluminosilicates.

50 In general the molecular sieve contacting operation is carried out in the vapor phase at 250° to 350° F. depending on boiling point of feed. The v./hr./v. is about 0.5 to 1. The operation is continued until the sieve is saturated with adsorbate (about 10-12 wt. percent on sieve). The adsorbate can be removed by a selective desorbent such as propylene which is then separated from the adsorbent by simple distillation. It can also be removed by raising the sieve temperature to 600° F. and lowering the pressure to 50 mm. Hg. The first technique is preferred since at 600° F. some polymerization of n-olefins can occur.

55 The contacting of the feed with the molecular sieve in the adsorption zone is conducted so as to remove from the feed substantially all (95 to 98 wt. percent) the normal hydrocarbons.

60 The normal hydrocarbon-free effluent is withdrawn. This effluent is then hydrogenated for complete saturation over a hydrogenation catalyst.

65 In conducting the hydrogenation of the effluent fraction in accordance with this invention, a wide variety of hydrogenation catalysts may be employed. Preferred catalysts constitute the oxides of cobalt or molybdenum.

in admixture and including cobalt molybdate. Other catalytic agents which can be used are platinum or nickel. Preferably these catalytic agents are supported on an adsorbent support such as alumina. It is particularly preferred to employ cobalt molybdate as the catalyst. The pressure employed is to be in the range of 25 to 500 pounds per square inch although it is preferred to use pressures below 400 p.s.i.g. for the hydrogenation of the effluent and it is particularly desirable to employ a pressure of about 200 p.s.i.g. Throughputs of 1 to 2 v./v./hr. may be employed although the preferred range is about 5 to 10 v./v./hr. The temperature maintained during hydrogenation is about 500° to 800° F. and specifically 700° F. Contact of the effluent with the catalyst under these conditions should be carried out employing a rate of hydrogen supply above about 1000 standard cubic feet of hydrogen per barrel, and generally about 2500 standard cubic feet per barrel.

The specific hydrogenation conditions are to be selected from the foregoing limits by regard to the resulting olefin saturation and/or hydrogen consumption. In general, for hydrogenation for complete saturation, hydrogen consumptions of about 450 to 600 standard cubic feet per barrel will be employed. In treating a typical effluent for complete olefin saturation, a hydrogen consumption of at least about 500 s.c.f./b. is ordinarily required.

The advantages of this invention will be better understood by reference to the following example and flow diagram.

Referring now to the flow diagram, a Baytown catalytic C₅ feed is fed through line 1 to a 5 Angstrom molecular sieve adsorption zone 2. The adsorbent may be arranged on trays or packed therein with or without supports. One adsorption zone has been shown for simplicity, but two or more can be used. The feed is at a temperature of 250° F. in the vapor phase and the flow rate is 0.5 v./v./hr. The feed had an initial Research octane number of 102.2 and a motor octane number of 88.3. Substantially all, e.g., 31 volume percent on feed of the normal hydrocarbons are adsorbed on the adsorbent in zone 2.

The effluent, free of normal hydrocarbons, is withdrawn from adsorption zone 2 through line 5 to hydrogenation zone 6. This effluent prior to the hydrogenation has a Research octane number of 103.5 and a motor octane number of 95. In hydrogenation zone 6 the effluent is hydrogenated at a temperature of 700° F. in the vapor phase over a cobalt molybdate on alumina catalyst. This effluent which contains about 38.5 vol. percent olefins is thus completely saturated. The conditions in hydrogenation zone 6 are a pressure of 200 p.s.i.g., a throughput of 2 v./hr./v. with a hydrogen consumption of about 150 s.c.f./b. The hydrogenated effluent is withdrawn through line 7 at a 70% yield on original total C₅ feed. Its Research octane number is 104.2 and its motor octane number is 100.0. This latter figure represents a marked increase.

The adsorbate on the molecular sieve is desorbed by the addition of propylene also at 250° F. Feed rate is 0.5 v./hr./v. The adsorbate is separated from the propylene by simple distillation and contains the following materials in the indicated yields.

Adsorbate:	Yield on feed
n-Pentane	5.0
n-Pentene-1	7.6
Cis Pentene-2	5.8
Transpentene-2	9.2
Pentadiene	0.4
C ₄ 's	3.2

This adsorbate is about 75% olefinic and can be utilized as a feed for chemicals. Because of the normal

character of the olefins they are excellent feeds for making alcohols, aldehydes, ethers and therefore command a high price.

The advantages of this invention will be apparent to the skilled in the art. A significant motor octane number improvement is obtained without the necessity of hydrogenating the total feed. Further, hydrogenation of the total feed would not produce a gasoline blending stock with both high Research and Motor octane number. 10 This is due to the fact that the Research octane number of normal olefins are degraded on hydrogenation. The motor octane number is only slightly improved. This is shown as follows:

	Research +3 ml. TEL	Motor +3 ml. TEL
n-pentene-1 ↓hydrogenation	98.6	82.9
n-pentane	88.7	83.6

Since all of the C₅ olefins in the adsorbate (31% on feed) would be converted to n-pentane, it is obvious that the octane number obtained by hydrogenation of the total C₅ feed would be inferior to the octane obtained by selective separation followed by hydrogenation of the isoparaffin-isolefin fraction. Thus this octane improvement is obtained with marked efficiencies in hydrogen use and equipment size.

30 It is to be understood that this invention is not limited to the specific examples which have been offered merely as illustrations and that modifications may be made without departing from the spirit of the invention.

What is claimed is:

1. A process for upgrading a catalytic C₅ hydrocarbon fraction containing isopentane, n-pentane, 2-methylbutene-1, pentene-1, cis-pentene-2, trans-pentene-2, and 2-methylbutene-2, which comprises the steps of passing the fraction through a molecular sieve adsorption zone 40 so as to remove therefrom substantially all the normal hydrocarbons n-pentane, pentene-1 cis-pentene-2 and trans-pentene-2; withdrawing the normal hydrocarbon-free effluent from the adsorption zone and hydrogenating the effluent for complete saturation of the 2-methylbutene-45 1 and the 2-methylbutene-2 therein in the presence of a hydrogenation catalyst.
2. The process of claim 1 in which the molecular sieve has pore openings of about 5 Angstroms.
3. The process of claim 2 in which the molecular sieve 50 contacting step is carried out in the vapor phase at a temperature in the range of 250° to 350° F. and a feed rate of 0.5/1 v./v./hr.
4. The process of claim 3 in which the C₅ hydrocarbon fraction has a boiling point in the range of 75° to 55 115° F.
5. The process of claim 4 including the additional step of desorbing the normal hydrocarbons from the sieve by treatment with propylene.
6. The process of claim 2 in which the molecular sieve 60 is a calcium alumino silicate.
